METAL SLIDE ASSEMBLY FOR TABLES

Wilbur S. Reed, Philadelphia, Pa.

Application September 1, 1950, Serial No. 182,867

4 Claims. (Cl. 311—71)

1

The present invention relates to table slides such as are ordinarily included in extensible tables of various types.

At the present time there are three general types of extensible tables. One of these is the so-called "split leaf" type in which the leaf which is to be inserted when the table is extended is of a two-part, hingedly-connected structure that is mounted on rods in the slide. The second is the so-called "straight leaf" type, in which the leaf to be added is one single straight piece that is normally supported by the slide beneath the table top when not in use. The third is the so-called "four leg" type, in which the slide assemblies at each side are simply connected together to form a one-piece slide construction.

Each of the several types of extensible table above mentioned includes a slide assembly at each side of the table to provide the sliding movement which is necessary for extending and collapsing the table. Obviously, one half of the table top is connected to an element of the slide assembly at each side thereof and the other half of the table top is connected to the complementary elements of the slide assembly.

The present invention has in view as its foremost objective the provision of a table slide which includes a pair of slide assemblies of distinctly novel construction and which presents certain decided advantages. This slide assembly may be generally characterized as including certain metallic parts which, when assembled, provide a channel which slidably receives one angle of an angle bar that is connected to one of the table top parts. Provision is made for maintaining the sides of the channel in accurately spaced relation and for limiting the sliding movement of the angle that is assembled therein.

More in detail, the invention has as an object the provision, in a table slide, of a slide assembly which consists essentially of a Z member, a pair of angles, and a channel member having outwardly extending flanges with the Z member and channel member assembled to provide the channel which receives the angle members.

Each of the angle members is formed with a pair of elongated slots which receive studs that extend between the Z channel members and which are spot welded in position. These studs function as spacers and as abutment means limiting sliding movement of the angles.

Various other more detailed objects and advantages of the invention, such as arise in connection with carrying out the above noted ideas in a practical embodiment, will in part become

2

apparent and in part be hereinafter stated as the description of the invention proceeds.

The invention therefore comprises a one-piece table slide including a slide assembly which consists essentially of a Z member, a pair of angles, and a channel member having outwardly extending flanges with the Z member and channel member assembled to provide the channel which receives the angle members.

For a full and more complete understanding of the invention, reference may be had to the following description and accompanying drawings, wherein:

Figure 1 is a top plan view of a table slide as designed in accordance with the precepts of this invention. The slide of this figure is for a table of the split leaf type;

Figure 2 is a view in side elevation of the slide shown in Figure 1 with a table top being shown in phantom outline;

Figure 3 is a view in end elevation with a table top, base and split leaf shown in a broken outline;

Figure 4 is a partial perspective showing the table top opened and with the split leaf in its collapsed out-of-the-way position;

Figure 5 is a detail perspective showing the several elements of one of the slide assemblies in exploded relation;

Figure 6 is a view showing one of the slide assemblies in elevation and the channel cross-pieces in section, of a slide designed for a table of the straight leaf type;

Figure 7 is a detailed plan view taken about on the plane represented by the line 7—7 of Figure 6 showing the connection of one of the cross channels to the slide assembly in one end thereof;

Figure 8 is a view similar to Figure 6 of a slide designed for a table of the four-legged type; and

Figure 9 is a bottom plan view taken about on the plane represented by the line 9—9 of Figure 8 showing the connection of one of the angle crosspieces to the slide assembly at one end thereof.

It is believed that the present invention is best described by first referring to Figure 5, which illustrates one of the slide assemblies which is present in each form of table slide. The slide assembly shown in Figure 5 is referred to in its entirety by the reference character A. This slide assembly A comprises a Z member which includes a vertically disposed main body portion 10, an upper outwardly extending flange 11, and a lower inwardly extending flange 12.

Mounted on the inner face of the main body

portion 10, substantially midway thereof, is a metallic strip 13 which is adapted to function both as a spacer, as will be later described, and also as an abutment member, limiting inward sliding movement of the angles to be later described.

At this point it is well to note that the Z member 10—11—12 is made from an appropriate sheet metal which is readily adapted to being stamped into the formation illustrated.

Also extending inwardly from the inner face of the main body portion 10 are four studs, 14, two being located on one side of the strip 13 and two on the other side.

A pair of angles are designated 15 and 16. 15 These angles are substantial duplicates and only one of them is here described in detail as that is sufficient to satisfy the purposes of this specification. Thus, each of the angles 15 and 16 has a top horizontal flange 17 that is provided with a plurality of openings 18 which are employed in securing a part of a table top to that respective angle. Each of the angles 15 and 16 also includes a vertical flange 19 that is formed with a pair of elongated slots 20. This flange 19 engages the inner face of the main body portion 10 of the Z member with the studs 14 being received in and extending through the slots 20.

A channel member comprises a vertically extending main body portion 21 and upper and lower flanges 22 and 23 which extend inwardly (speaking with reference to a complete slide assembly). This channel member is intended to be assembled on the Z member so as to maintain the angles 15 and 16 in position between the main body portion 10 of the Z member and the main body portion 21 of the channel member. To this end the exposed face of the main body portion 21 is provided with a plurality of markings or scorings 24 which correspond in location to the studs 14 and the strip 13. After the channel member has been positioned so that the main body portion 21 engages the free ends of the studs 14 and the exposed face of the strip 13, it is spot welded to these elements at the points indicated at 24, thus providing a permanently assembled slide assembly. When so assembled, the flange 23 of the channel member engages the flange 12 of the Z member and these two flanges are also secured together by being spot welded at appropriate intervals, such as indicated at 25 in Figure 1.

Referring now more particularly to Figures 1 to 4 inclusive, a one-piece table slide that is intended for use with a table of the split leaf type will now be described. This table slide, which is referred to in its entirety by the reference character S, comprises a pair of slide assemblies A. Extending between these slide assemblies A are two cross bars 26 and 27. These cross bars 26 and 27 are of duplicate construction. Each of them is a channel bar comprising a main body portion 28 that is disposed horizontally, and upwardly extending flanges 29 which are flared outwardly at each end, as indicated at 30, to provide a flattened out end construction 31 that is secured to the composite flange construction 12 and 23 by spot welding, as indicated at 32. Beginning with the flattened out end portion 31 and extending inwardly an appreciable distance, the main body portion 28 is formed with an elongated slot 33.

Extending downwardly from the inner flange 29 of each of the cross channels 26 and 27 is a

tab or ear 34, with the two tabs being formed with aligned openings, which receive a roller rod 35. This roller rod 35 is maintained in assembled relation by small protuberances 36 which may be struck from each end thereof.

Extending upwardly on the inner flange 29 of each of the cross channels 26 and 27 is a tab or ear 37. These ears 37 are formed with aligned openings which receive a swivel bar 38. 10 The latter is maintained in assembled relation by projections 39 which are struck from the metal of the bar. Intermediate its ends, the swivel bar 38 is formed with two offset portions 40 that are flattened out and formed with openings 41.

As shown in Figure 4, a split leaf L comprises two halves 42 and 43 that are hingedly connected together as indicated at 44. The half 42 is connected to the swivel bar 38 by screws 20 45 which pass through the openings 41. The half 43 rests on the roller 35 when the leaf L is folded up in inoperative position.

A table top comprises two halves, 46 and 47, which are secured to the flanges 17 of the angles 15 and 16 by fastening members which pass through the openings 18.

A base is shown in broken outline in Figure 3 and is referred to by the reference character B. This base is of the Duncan Phyfe type and includes the legs 48, the upper ends of which are secured to the cross channels 26 and 27 by an appropriate fastening means, such as bolts which pass through the slots 33. Obviously these slots 33 accommodate variations in the size of the base B.

The operation of the split leaf table, illustrated in Figures 1 to 4 inclusive, is believed to be obvious from the description of the parts given.

It may be briefly outlined by noting that when an increased area of the table top is desired, the two parts 46 and 47 are first slid apart into the position depicted in Figure 4. This movement is accommodated because the angles 15 and 16 will slide in the channels provided by the Z member 10—11—12 and channel member 21—22—23, the outward sliding movement being limited by the studs 14 which are received in the slots 20.

The leaf L is now manipulated by swinging the half 42 about the swivel 38 as a pivot. This depresses that end of the two leaves folded together so as to raise the opposite end. This causes the free end of leaf half 43 to rise up and slide over the slide assembly at that side and as the movement is continued, the halves are opened up into the position of a leaf which fills the gap between the table top parts 46 and 47. The latter are now closed against the leaf L to give a finished appearance.

When the table is to be closed, the exact opposite of the operation above described takes place. The top parts 46 and 47 are first extended sufficiently to clear the leaf L for manipulation. The half 42 is first raised and swung about the swivel 38 with the lower half riding on the roller 35 into the position depicted in Figure 4, after which the table top parts 46 and 47 may be closed over the folded leaf.

First modification

A one-piece table slide for a table of the straight leaf type is substantially the same as that above described, with the changes being depicted in Figures 6 and 7. With such a table slide two of the slide assemblies A are employed, one being located at each side. Two cross bars 26 and 27

are also utilized. These cross bars are of channel construction, but the flanges 29 extend downwardly from the bases 28 rather than upwardly therefrom. Moreover, the roller 35 and swivel bar 38, together with the construction which is necessary for their mounting, is eliminated. When the table is in its contracted position, the straight leaf rests on the cross bars 26 and 27 beneath the table top. Due to the fact that the flanges 29 extend downwardly, the corners which are formed thereby are rounded. Thus the leaf may be slid over these corners without danger of marring.

When the table is to be extended to provide increased area in the top, the two top parts which are connected to the flanges 17 of the angles 15 and 16 are moved apart in the manner described and the leaf removed from its position on the crosspieces 26 and 27 and laid across the two slide assemblies, whereupon the top parts are closed against the leaf to provide a finished appearance.

Second modification

When a one-piece table slide is to be provided for a table of the four-legged type, two of the slide assemblies A are employed, one being located at each side of the slide. These slide assemblies are connected by two crosspieces 9 and 49. These crosspieces 9 and 49 take the form of angles such as shown in Figures 8 and 9. One flange of each angle is secured to the composite flange 12-23 of the slide assemblies, as by spot welding, as indicated at 50, and the other flange extends downwardly.

While preferred specific embodiments of the invention are hereinbefore set forth, it is to be clearly understood that the invention is not to be limited to the exact constructions, mechanisms and devices illustrated and described because 40 various modifications of these details may be provided in putting the invention into practice within the purview of the appended claims.

What is claimed is:

1. In a table slide, a slide assembly comprising a Z member, a channel member cooperating with said Z member to provide a channel, and a pair of angle members, each having a flange slidably received in said channel and a second flange adapted to be secured to a part of a table.

2. In a table slide, a slide assembly comprising a Z member having a main body portion, an outwardly extending flange and an inwardly extending flange, a channel member having a main body portion spaced from the main body portion of said Z member to provide a channel, and a

pair of angle members each having a flange slidably received in said channel and another flange overlying the outwardly extending flange of said Z member and adapted to be connected to a part of a table top.

3. In a table slide, a slide assembly comprising a Z member having a main body portion, an outwardly extending upper flange and an inwardly extending lower flange, a plurality of studs 10 extending inwardly from the inner face of said body portion, a pair of angle members, each of said angle members having a flange overlying the main body portion of said Z member and formed with slots receiving said studs and a flange 15 overlying the upper outwardly extending flange of said Z member, and a channel member having a main body portion secured to said studs and cooperating with the main body portion of said Z member to provide a channel in which 20 said angle members slide.

4. In a table slide, a slide assembly comprising a Z member having a main body portion, an outwardly extending upper flange and an inwardly extending lower flange, a plurality of studs 25 extending inwardly from the inner face of said body portion, a strip on the inner face of said main body portion substantially midway between the ends thereof, a pair of angle members each having a flange overlying the main body portion 30 of said Z member and formed with slots receiving certain of said studs, each of said angle members also having a flange overlying the outward upper flange of said Z member and formed with openings whereby it is adapted to be connected to a part of a table top, and a channel member 35 having a main body portion and upper and lower inwardly extending flanges, said main body portion being welded to said studs and strip with the lower flange of said channel member being welded to the lower flange of said upper member.
